STITCH REGULATOR AND REVERSING
MECHANISM FOR SEWING MACHINES

Clarence S. Best, Belvidere, Ill., assignor to National Sewing Machine Company, Belvidere, Ill., a corporation of Illinois

Application May 15, 1939, Serial No. 273,596

4 Claims. (Cl. 112—210)

This invention relates to stitch regulator and reversing mechanism for sewing machines whereby the length of the stitches may be regulated and the direction of movement of the feed may be controlled.

The main object of my invention is to provide stitch regulator and reversing mechanism which may be controlled by the operator by manipulation of a single element, preferably located on the bed of the sewing head, adjacent to and forwardly of the upright standard, in a position most accessible to the right hand of the user.

Another object of the invention is to provide a feed-regulating lever which is accurate and reliable in use and provided with indicating means enabling the operator to obtain the desired feed adjustment.

Another object is to provide a feed regulating lever which is directly connected with cam means located beneath the bed plate of the sewing head, the adjusted position of said cam means controlling both the direction and extent of movement of the feed dog on which the work rests.

In the drawings:

25 Fig. 1 is a front elevation of a sewing machine embodying my invention.

Fig. 2 is a horizontal sectional view, taken in the plane of the line 2—2 of Fig. 1.

Figs. 3 and 4 are transverse vertical sectional views, on an enlarged scale, taken in the planes of the lines 3—3 and 4—4, respectively, of Fig. 1.

Fig. 5 is a transverse vertical sectional view, showing some of the parts shown in Fig. 4, but in different positions, taken in the plane of the line 5—5 of Fig. 1.

Fig. 6 is a bottom plan view of the machine.

Fig. 7 is a vertical sectional view, taken in the plane of the line 7—7 of Fig. 8.

Fig. 8 is a transverse vertical sectional view, taken in the plane of the line 8—8 of Fig. 1, showing on an enlarged scale the feed regulating lever and adjacent parts.

In that embodiment of the invention shown in the drawings, the bed plate of the sewing head is indicated at 10, four legs at 11, the upright standard at 12 and overhanging arm at 13. A motor 14 drives the fly wheel 15 for actuating the stitch forming mechanism, which is not described herein in detail because the invention is directed to means for controlling the direction and extent of movement of the feed dog 16 movably mounted in the bed plate 10. A presser foot is indicated at 17 and the work at 18.

The manually operable adjusting means whereby the operator controls the length of the stitches

and direction of movement of the work is shown in Figs. 1, 2, 7 and 8. Said means comprises a plate 19 cut away at 20, secured to the bed plate 10 by screws 21. The part 22 is curved longitudinally as shown and is marked with 5 stitch-length indicating means. The part 23, partly underlying the plate 19, is a strip of substantially V-form between flat ends, but the center or bottom of the V is flat as indicated at 24 in Figs. 7 and 8, the bed plate 10 being cut 10 away beneath the slot 20 and member 23.

A feed control lever 25 extends through the slot 20. At its upper end it is provided with a pointer 26 which projects forwardly above the scale 22, and a screw threaded ear 27 in which 15 is mounted an adjusting screw 28. A collar 29 on the screw 28 limits its upward movement relatively to the ear 27 of the lever 25. The lower end of said lever 25 is pivotally mounted on a pin 30 which extends through said lever end and is 20 fixed in the forward right hand leg 11.

When the screw 28 has been screwed downwardly as shown in Fig. 8 and in full lines in Fig. 7, the bottom of the screw touches lightly the flat part 24 of the V-member 23, and the 25 possible movement of the screw, longitudinally of said member 23, is limited to the length of said flat part 24, and consequently only slight pivotal movement can be transmitted to the feed control lever 25. When the screw has been 30 screwed upwardly, the lower end of the screw contacts one or the other of the side walls of the V-portion of the member 23, as shown in dotted lines in Fig. 7, and movement of the lever 28 by manually grasping the head of the screw 35 28 imparts increased pivotal movement to the lever 25, for the purposes to be described.

The feed control lever 25 has a pin 31 projecting from it rearwardly and horizontally, slightly beneath the bed plate 10, into engagement with a sleeve 32, diagonally slotted at 33, said sleeve being fixed on a crank shaft 34, as shown in Figs. 1, 6, 7 and 8. The shaft 34 is rotatably mounted in bearings 35 and 36 fixed on the lower surface of the bed plate 10. While 45 the shaft 34 is rotatably mounted in said bearings, it has limited rotative movement only, in opposite directions, imparted by manipulation of the lever 25 in the slot 20, and resultant rotative movement of the shaft 34 due to the engagement 50 of the pin 31 in the slotted sleeve 32 on said shaft.

The shaft 34 has fixed to that end adjacent the bearing 36 a crank cheek 37, the latter being pivotally connected by a crank pin 38 to a crank 55

cheek 39 fixed to a pin 40, on which are pivotally mounted the arms 41 formed on the upper end of a link 42. The lower end of said link 42, in the form of a sleeve 43, is connected by a pivot 5 pin 44 to a bell crank lever comprising a bifurcated arm 45 integrally formed on a rock shaft 46 having ends 47 mounted at one end in a bearing 48 and at the other end in the forward left hand leg 11, at 49, the other arm of the bell 10 crank lever being indicated at 50.

As best shown in Figs. 1 and 3, the lever 50 extends upwardly from the rock shaft 46 substantially at right angles to the arm 45 (Figs. 3, 4 and 5). Said lever 50 is pivotally connected 15 at 51 to a feed bar 52 which extends transversely under the bed plate 10 beneath the feed dog 16. Said feed dog 16 is fixedly mounted on the bar 52 by depending ears 53 as indicated at 54.

The rearward end 55 of the bar 52 is pivotally connected at 56 to a lever 57, pivotally connected at 58 to a lever 59 integral with a rock shaft 60 having ends 61 supported in a bearing 62 and in the rearward left hand leg 11 at 63. The lever 59 is pivotally connected at 64 to a 25 bifurcated arm on the sleeve 65 eccentrically mounted at 66 on the rotatable shaft 67 mounted in the bearings 68 and 69 (Figs. 3 and 6).

Also eccentrically mounted on said shaft 67, as shown at 70, is the eye end 71 of a curved 30 arm 72, pivotally mounted at 73 (Fig. 1) on the pin 40, between the sleeve members 41 of the link 42.

Within the housing 74 formed on the bottom of the bed plate 10 are conventional gears 75, 76, 35 driven by a gear 77 operatively connected to the motor shaft. The gear 75 drives the shaft 67 and the gear 76 drives the shaft 78 which operates the stitch forming means within the housing 79.

The operation of the parts described is as follows: The operator adjusts the screw 28 according to the size of stitch desired, raising it relatively to the ear 27 of the feed control lever 25 if a long stitch is desired, and lowering it to obtain a short stitch. The screw is adjusted after the position of the pointer 26 has been selected, 45 and contact of the lower end of the screw with the member 23 determines the position of the lever 25 at either side of the center of the slot 28, according to the direction in which it is desired to move the feed dog 16 and work 18. The adjustment of the screw 28 and lever 25 thus determines the point at which the pin 31 on the lever will engage the slot 33 in the sleeve 32, thereby 50 rotating the shaft 34 to predetermined position. This results in fixing the crank 37 in one of its possible positions, as in Fig. 4, which position it retains until the lever 25 is moved, either to the opposite side of the slot 28 to reverse the direction of movement of the feed dog 16, as in Fig. 5, 55 or by adjusting the screw 28 to change the length of the arc in which the lever 25 can travel, whereby the stitch length is controlled.

The rotation of the shaft 34 results in pivotal movement of the crank cheek 39, bodily movement of the pin 40, pivotal movement of the link 42, and pivotal movement of the bell crank lever arms 45-50 about the axis of the rock shaft 46, the lever arm 50 moving the feed bar 52 to one of its two positions, for forward or reverse movement of the feed dog 16. By reason of its pivotal connection with the pin 40, the curved arm 72 on the shaft 67 is also moved by adjusting the shaft 34.

When the sewing mechanism is actuated, the rotation of the shaft 67 effects the feed dog lifting operation, intermittently, by means of the

eccentric 66, sleeve 65, levers 59, 57, and link 55 on one end of dog 16. The eccentric 70, curved arm 71-72-73, pin 40, link 42, and bell crank lever 45-50 transmit reciprocating movement to the bar 52 and dog 16 transversely of the bed 5 plate 10.

Changes may be made in details of construction without departing from the scope of my invention.

I claim:

1. Stitch regulating and reversing mechanism for sewing machines comprising a slotted bed plate, a feed dog transversely movable in the bed plate, an upright standard and overhanging arm, a feed lever extending through said slotted bed 15 plate forwardly of the upright standard, the feed lever being pivotally mounted on a fixed support beneath the bed plate, a horizontally disposed stitch length indicating scale on the bed plate forwardly of the lever, a flat bottomed V-shaped 20 member in the bed plate rearwardly of the feed lever, an adjusting screw mounted on the lever for contact with the V-shaped member, a pointer on the lever adjacent said scale, and operative connections between the feed lever and the feed 25 dog for moving the dog to predetermined position.

2. In stitch regulating and reversing mechanism for sewing machines, a bed plate, a horizontally disposed slotted plate mounted on the bed plate, said slotted plate having a stitch 30 length indicating scale on one side of the slot and a substantially V-shaped member on the other side of the slot, a feed lever extending through the slot, said lever having a pointer on the side adjacent said scale and adjustable means 35 on the other side for contact with said V-shaped member.

3. In stitch regulating and reversing mechanism for sewing machines, a bed plate, a horizontally disposed slotted plate mounted on the 40 bed plate, said slotted plate having a stitch length indicating scale on one side of the slot and a substantially V-shaped member on the other side of the slot, a feed lever extending through the slot, said lever having a pointer on the side adjacent 45 said scale and adjustable means on the other side for contact with said V-shaped member, said stitch length indicating scale being convex on its upper surface and said pointer overlying said scale in close proximity thereto throughout the 50 movement of said feed lever.

4. Stitch regulating and reversing mechanism for sewing machines comprising a bed plate, a feed dog mounted in the plate, an upright standard, the bed plate being slotted longitudinally 55 forwardly of the standard, a vertically disposed feed control lever pivotally mounted beneath the bed plate, extending through said slot and operable above the plate by movement longitudinally 60 of the bed plate, a cam shaft rotatably mounted beneath the bed plate and parallel to the vertical plane in which the feed control lever moves, a spirally grooved member fixed on the cam shaft, means on the feed control lever between the bed 65 plate and the pivotally mounted end of said lever in engagement with the spirally grooved member on the cam shaft, and operative connections between the cam shaft and the feed dog, movement of the feed control lever longitudinally of 70 the bed plate controlling the position of the cam shaft and thereby determining the direction of movement and length of movement of the feed dog.
